UNITED STATES PATENT OFFICE.

JOSEPH PEYSER, OF MOUNT VERNON, NEW YORK.

SEPARATING AND FEEDING MEANS.

Application filed December 31, 1926. Serial No. 158,396.

This invention relates generally to separating and feeding means for containers or the like; and has more particularly reference to a device in which containers, such as 5 tin cans, may be separated, spaced and accelerated during their travel, the main object and feature of the invention being the provision of simple means whereby the separation, spacing and acceleration may be 10 performed in a positive manner.

In the accompanying drawings, the invention is disclosed in a concrete and now preferred form by way of illustration and in 15 said drawings:

Fig. 1 is a plan view of a device embodying the invention with parts broken away and in section for clearness of illustration;

Fig. 2 is a side elevation of the parts shown in Fig. 1.

When certain manipulations such as heading, are to be performed on containers, it is necessary to advance them in spaced relation and at a certain speed to the machine for acting upon them; and, as containers or 25 bodies come in a crowded condition from other machines, it is necessary to separate and space them and to accelerate them up to the speed of the machine that is subsequently to act upon them.

1 indicates a support, in this case a rotatable dial to which the bodies are fed promiscuously, although in an upright position, at the point denoted by arrow 2, and from 35 which they are fed in properly spaced relation and at an accelerated speed, at the point denoted by arrow 3, from whence they pass to the desired machine. 4 indicates a separating and feeding member of which there may be a number associated with said

disc. In the present instance, these members are carried by said disc and work in slots 5 of the disc. 6 is a curved guideway formed by walls 7 and 8 and this curved guideway is eccentric, that is, the bodies A 40 in passing through it are moved outwardly away from the center of rotation of the dial and therefore the speed of the bodies is accelerated. In contradistinction to devices heretofore employed, members 4 do not move 45 merely up and down in the slots but move bodily across the curved guideway. By these means, separation is absolutely assured, which is not the case when members as 4 are moved up and down. In other words, 50 the timing does not have to be so accurate. It will also be seen that said members move

outwardly or are projected outwardly substantially radially of the orbit of said members and therefore non-radially with respect to the center of the curve of the guideway. 60 In the present instance, each member is pivotally supported on a center, as 9, and there is a stationary cam 10 beneath the dial common to all members 4. Also, each member 4 is provided with a taper separating surface 65 11 and, at an angle thereto, with a propelling surface 12. In operation cam 10 acts to turn each member 4 on its pivot, by reason of cam roll 13 carried by said member, thereby bringing the taper surface outwardly between the bodies so as to separate them. Member 4 moves bodily across the guideway and finally comes to a position 70 below the slot in the dial. Propelling surface 12, however, remains above the slot 75 and continues to act on the container. Due to the combined action of members 4 and the curved guide, the bodies are gradually separated, spaced and accelerated. Guide 6 extends only over a portion of dial 1 and the 80 shape of cam 10 is such that during that portion of their travel, when said members are outside the guideway, they are returned through the slots to their original position ready for the next operation. 85

I claim:

1. Separating and feeding means for bodies comprising: a rotatable dial to receive bodies, having a plurality of substantially radial slots, an eccentric guideway 90 above the dial, a plurality of separating and feeding members carried by said dial, and actuating means to move said members through said slots and bodily across the guideway between the bodies. 95

2. Separating and feeding means for bodies comprising: a rotatable dial to receive bodies, having a plurality of substantially radial slots, an eccentric guideway extending over a portion of said dial, a plurality of separating and feeding members carried by said dial, and actuating means to move said members through said slots and bodily across the guideway between the bodies and back again to their original position through said slots when said members are traveling outside the guideway. 100 105

3. Separating and feeding means for bodies comprising: a rotatable dial to receive bodies, having a plurality of substantially radial slots, a plurality of separating and feeding members carried by said dial, 110

and actuating means to move said members through said slots and bodily across the dial between said bodies.

4. Separating and feeding means for bodies comprising: a rotatable dial to receive bodies, having a plurality of substantially radial slots, a plurality of separating and feeding members carried by said dial, and actuating means to move said members through said slots and bodily across the dial between said bodies during one portion of the rotation of the dial and back again to their original position through said slots during another portion of the rotation of the dial.

5. In separating and feeding means for bodies, a rotatable dial to receive bodies, having a substantially radial slot, a pivotally supported separating and feeding member carried by said dial, said member having a 20 taper separating surface and, angularly disposed thereto, a propelling surface, actuating means for turning said member on its pivot to cause first said taper surface and then said propelling surface to move 25 through said slot and bodily across the dial.

Signed at New York, in the county of New York and State of New York, this 27th day of December, 1926.

JOSEPH PEYSER.
